UNITED STATES PATENT OFFICE.

JACOB DIEHL, OF SHEBOYGAN, WISCONSIN.

CLAMP.

1,063,832.

Specification of Letters Patent.

Patented June 3, 1913.

Application filed May 10, 1912. Serial No. 696,525.

To all whom it may concern:

Be it known that I, JACOB DIEHL, a citizen of the United States, residing at Sheboygan, in the county of Sheboygan and 5 State of Wisconsin, have invented a new and useful Clamp, of which the following is a specification.

The present invention relates to improvements in clamps, the primary object of the 10 invention being the provision of a novel form of what is known as C-clamp, in which the screw is so braced as to prevent any torsional strain being thrown thereon during the movement to and from work engaging 15 position, while in the opposite end of the member is provided either a single or a plurality of abutting members that are connected to the clamp by means of a universal or ball-and-socket joint, thus providing a 20 means whereby various shaped objects may be properly clamped between the screw and abutting members.

A further object of the present invention is the provision of a novel mounting of 25 lower abutting member, the same being swivelly connected to the clamp body and carrying either a single or a plurality of abutments connected thereto through the medium of a universal joint, whereby said 30 abutments will conform to the contour of the object clamped and provided with the usual screw a medium for securely holding the work within the clamp.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed can be made within the scope of what is claimed without departing from the spirit of the invention.

In the drawings—Figure 1 is a side elevation of the complete clamp provided with 45 two lower abutting members. Fig. 2 is a section taken on line 2—2 of Fig. 1. Fig. 3 is a section taken on line 3—3 of Fig. 1.

Referring to the drawings, the numeral 1 50 designates the frame which is of the usual form, the upper arm 2 of which is provided with the spaced lugs 3 and 3' which provide

the space 4 therebetween, the said lugs 3 and 3' being provided with the alined inferiorly threaded apertures 3^a for the reception of the clamping screw 5. This clamping screw 5 is provided with the actuating knob or handle 6 at the upper end, and upon the lower end thereof is formed a sphere or ball 7 which is fitted within the malleable 60 fingers 8 which constitute a socket and carry the abutting plate 9, thus providing a means whereby said abutting plate may assume various angles when engaging the work.

By the means of the spaced lugs 3 and 3', it will be seen that the screw is braced at two points and thereby the same is held against any binding action due any torsional strain thrown upon the screw 5 when in clamping position. The lower terminal 70 10 of the clamping frame 1 is provided with the enlarged portion 11 in which is mounted the pin 12 which constitutes a journal for the lugs 13 of the two plates 14 which are held together and in relative position to each 75 other by means of the riveting pins 15. These two plates 14 constitute the lower swiveled abutment carrying member and are so disposed with relation to the terminal 10 as to have an oscillatory movement longitudinally of the arm 10 and are each provided with the respective spherical sockets 16, in the present instance two being shown, in which are mounted the balls or spheres 17 provided with shanks 18, and each carrying 80 its respective abutment plate 19. By this means it will be seen that the respective plates 19 may be tilted to conform to the surface clamped between the said plates 19 and the plate 9 carried by the screw 5. It 85 will thus be seen that any shape of work may be properly clamped between the plates 9 and 19 and that by reason of the spaced lugs 3 and 3', the torsion thrown upon the screw 5 will be properly taken care 90 of and the screw 5 will always travel in the desired position guided by said lugs 3 and 3'.

What is claimed is:

A C-clamp, having a screw fitted in one terminal, an abutment plate connected to the 100 screw by a ball-and-socket joint, two plates connected together and having terminal straddling lugs pivoted astride the other terminal of the clamp for back and forth

swinging movement relatively to the abutment plate of the screw, and two abutment plates connected each by a ball-and-socket joint to the two swinging plates and for co-operation with the abutment plate of the screw.

In testimony that I claim the foregoing

as my own, I have hereto affixed my signature in the presence of two witnesses.

JACOB DIEHL.
